12 Claims. (Cl. 196—41)

1

This invention relates to an improved method of refining lubricating oils. Particularly, it relates to a solvent extraction process whereby the organic acid content of lubricating oils may be effectively reduced.

Lubricating oil distillates derived from naphthenic and mixed base crude petroleum oils frequently contain appreciable quantities of naturally occurring organic acids. These organic acids, such as naphthenic acids, even if present in a lubricating oil in relatively small concentrations, are corrosive to engine parts at the high temperatures to which such oil is usually subjected. It is important, therefore, that motor lubricants not only have satisfactory viscosity index, color, pour and stability characteristics, but also contain organic acids in concentrations insufficient to cause corrosion difficulties under severe temperature conditions.

In present commercial practice, it is customary to improve the viscosity index characteristics of untreated lubricating oil distillates by treatment in the liquid phase with a solvent that has a preferential selectivity for the low viscosity index naphthenic- and aromatic-type (relatively less paraffinic-type) compounds as compared with the high viscosity index (relatively more paraffinic-type) compounds. Phenol, furfural, aniline, nitrobenzene and the like are typical solvents used for this purpose. Solvents, such as phenol, that do not react with organic acids also demonstrate a preferential selectivity for organic acids of the type usually found in lubricating oil distillates derived from naphthenic or mixed base crudes. In a solvent treating process, therefore, the organic acids tend to be separated from the paraffinic constituents. It has been observed, however, that lubricating oil distillates containing relatively high concentrations of organic acids may be treated with a selective solvent to produce a finished lubricating oil having satisfactory viscosity index characteristics and yet retain sufficient organic acids to render the solvent treated oil corrosive to engine parts.

Experience has shown that motor lubricants derived from mixed base and naphthenic crudes should contain organic acids in amounts below, i. e. having a neutralization value below, an equivalent of 0.1 milligram KOH per gram of oil to render said lubricant non-corrosive to engine parts. Experience also has shown that the liquid phase extraction of lubricant distillates containing organic acids in amounts below an equivalent of one milligram KOH per gram of said distillate with a solvent, such as phenol, gener-

ally produces high yields of a finished lubricant having a high viscosity index and containing non-corrosive amounts of organic acids. It has been found, for example, that lubricant distillates containing organic acids in amounts substantially above an equivalent of one milligram KOH per gram of said distillate require solvent extracting to a lower yield of finished lubricant having a higher viscosity index than is normally required in order to reduce the organic acid content of said lubricant to non-corrosive amounts. Such a motor lubricant is said to be "over extracted"; that is, one requirement imposed on the finished lubricant is met at the expense of other requirements imposed thereon.

In order to effect a substantially complete removal of the organic acids from the high viscosity index paraffinic constituents, it is frequently necessary to increase the severity of the solvent treat, that is, increase the ratio of solvent to lubricating oil, above the normal required to produce an oil of desired viscosity index. Increasing the solvent treat decreases the yield of finished lubricating oil obtained in the treating process. In addition, if the solvent treating equipment is operated at its maximum capacity, an increase in solvent treat above normal necessitates decreasing the amount of oil feed which may be introduced. Increasing the severity of the solvent treat also is disadvantageous in that natural inhibitors present in certain types of lubricating oil distillates and known to be beneficial to motor lubricants are removed from the finished lubricant.

An alternative method of reducing the organic acid content of motor lubricants is that of treating a topped crude or lubricating oil distillate with an alkaline material. For example, it is well known to the art to remove organic acids present in petroleum oil fractions by distilling a reduced crude in the presence of caustic or other alkaline materials. This procedure has certain disadvantages in that salts of the organic acids and extraneous alkaline material remain in the distillate residue. If the amount of the alkaline materials remaining in the residue is relatively high, the residue may be unsatisfactory for asphalt manufacture or for use as a fuel oil.

In U. S. 2,451,025, issued October 12, 1948, to Harold L. Ellender, a method is described for removing organic acids from lubricating oil distillates in a process involving treating a lubricating oil distillate during distillation thereof with an alkaline reagent, such as sodium hydroxide, following which a fraction boiling in the

lubricating oil boiling range is extracted with a solvent, such as phenol, to obtain a raffinate having lubricating oil qualities and a low neutralization value within the limits of the specification. This process is quite effective and allows the obtaining of a solvent raffinate having the desired characteristics without requiring the lubricating oil to be overextracted in the solvent extraction step to produce a product having the requisite low neutralization value. It will be seen, however, that the aforesaid Ellender patent requires the addition of an alkaline reagent to the distillation zone in which the mineral oil lubricating fraction is being segregated from a topped crude petroleum. Thus, under some conditions the presence of the alkaline reagent in the distillation tower may be harmful, especially when long contact times are employed and excessive amounts of the alkaline reagent are necessary since the presence of alkaline reagents, such as sodium hydroxide, may affect deleteriously the ferrous metals employed in distillation towers. It is well known that sodium hydroxide may cause caustic embrittlement of ferrous metals when in contact therewith at high temperatures.

It is, therefore, the main object of the present invention to provide an improved process for refining mineral lubricating oils.

Another object of our invention is to provide an economical process wherein maximum yields of solvent extracted lubricating oils, meeting both viscosity index and organic acid content requirements, may be produced from suitable mineral oils.

A still further object of our invention is to provide a selective solvent extraction process in which maximum quantities of oil and minimum quantities of solvent are circulated to produce lubricating oil of desired high viscosity index and low organic acid content without overextracting the oils.

Still other objects and advantages will be apparent to workers skilled in the art to which the present invention relates.

In accordance with the present invention, it has now been found that lubricating oil fractions obtained from crude petroleums and mineral oil distillates may be solvent extracted to obtain a solvent raffinate having the required low neutralization value without overextracting the oil. Thus, for example, in accordance with the present invention, a lubricating oil fraction, such as a mineral oil distillate boiling in the lubricating oil boiling range and having lubricating oil components therein is subjected to extraction with phenol, such as anhydrous or aqueous phenol, containing a small but effective amount of an alkali metal phenolate which may be formed in situ by adding an alkali metal hydroxide to the phenol, under conditions to form an extract phase and a raffinate phase which are recovered separately. The raffinate phase, from which the undesirable components have been removed in the phenol, is subjected to a stripping operation in which the residual phenol is removed therefrom to allow recovery of the desirable motor oil fractions which, by virtue of the presence of the alkali metal hydroxide or phenolate during the extraction operation in the presence of phenol, allows the obtaining of a motor oil 70 having the required low neutralization value.

Alternatively, depending on the characteristics of the oil and, therefore, the treating operations to which the oil may be subsequently subjected, the alkali metal hydroxide may be added either 75

to the phenol prior to contact with the oil being extracted or to the solvent raffinate containing the phenol. Addition of the alkali metal hydroxide converts a small amount of the phenol to the corresponding phenolate which, it is believed, by reaction with the organic acids releases the alkali metal hydroxide which serves to neutralize the organic acids.

Therefore, it is within the purview of our invention to add alkali metal phenolates rather than alkali metal hydroxide to the phenol. Therefore, the invention may be described briefly as involving maintaining alkali metal phenolate in the phenol solvent and solvent extracting the lubricating oil fraction with the mixture of alkali metal phenolate and phenol under conditions to form a raffinate phase and an extract phase, the two phases being separately recovered and processed for recovery of phenol and the hydrocarbons contained in the two phases.

In the foregoing brief description, it is seen that the essence of the present invention resides in providing a process in which a lubricating oil fraction, such as a mineral oil distillate, is subjected to contact with phenol containing a small amount of an alkali metal phenolate which may be formed in situ by adding to the phenol a small but effective amount of an alkali metal hydroxide. The presence of alkali metal phenolate in a small but effective amount in the phenol causes the removal of the organic acids and allows the obtaining of a solvent raffinate having a neutralization value no greater than 0.1 milligram KOH per gram of oil without overextraction of the oil. As mentioned before, an alternative mode of the present invention involves adding the alkali metal phenolate to the solvent raffinate containing phenol or forming the alkali metal phenolate in the solvent raffinate containing phenol to obtain a motor oil fraction having the desired low organic acid content.

The invention will be better understood by reference to the single figure which is a diagrammatic flow plan of a preferred mode of practicing the present invention.

Referring now to the drawing, numeral 11 designates a solvent extraction zone which may be a single extraction tower or a plurality of extraction towers provided with suitable internal contacting equipment such as bell cap trays, packing, and the like to allow intimate contact between the mineral oil distillate boiling in the lubricating oil boiling range and having lubricating oil qualities which is introduced into zone 11 by line 12 and flows upwardly therein contacting the down-flowing phenol which is introduced into zone 11 by line 13. The phenol introduced by line 13 may be substantially anhydrous phenol; that is, it may have a phenol content of approximately 100% or it may be aqueous phenol containing approximately 10% of water. Thus, it is understood that phenol containing 90% to 100% phenol may be introduced by line 13 and employed as a solvent in solvent extraction zone 11. Conditions are adjusted in extraction zone 11 to produce a raffinate phase and an extract phase. Such conditions are well known to the art, but will be given in more detail hereinafter.

The phenol, prior to introduction into zone 11, has added to it by line 14 controlled by valve 15 a small but effective amount of sodium hydroxide which is withdrawn from tank 16 by pump 17. The amount of sodium hydroxide introduced into the phenol to cause the formation

in situ of sodium phenolate will generally depend on the organic acid content of the mineral motor oil distillate introduced by line 12 and the extent to which it is desired to remove such acids. The mineral motor oil distillate may have an organic acid content corresponding to a neutralization value of approximately 3.5 milligrams KOH per gram of oil. Usually, however, the neutralization value will be somewhat lower and may be about 2 milligrams KOH per gram of oil. In any event, oil having a neutralization value of above about 1.0 milligram KOH per gram of oil is generally too high to allow the production of a raffinate having the desired neutralization value no greater than about 0.1 milligram KOH per gram of oil without overextracting the oil. Therefore, the amount of sodium hydroxide or sodium phenolate introduced or contained in the phenol should usually at least be the theoretical amount required to allow the obtaining of a solvent raffinate having a neutralization value of no greater than about 0.1 milligram KOH per gram of oil. In cases where it is not necessary to obtain extracted oils having such low neutralization values or in the event the oil to be extracted has a low neutralization value, such as below 1.0, and requires a light solvent treat, it may not be necessary to maintain the alkali metal hydroxide or phenolate content of the solvent at the theoretical amount. Generally, the amount of alkali metal phenolate maintained in the solvent should, on a molar basis, be equivalent to from 0.2 to 3.0 times the theoretical amount of KOH required to neutralize acidic bodies in the oil to be extracted.

As mentioned before, the phenol containing the sodium phenolate either added thereto or produced in situ contacts countercurrently the ascending mineral motor oil distillate in extraction zone 11 and by adjustment of conditions therein, causes the formation of raffinate and extract phases. The extract phase is withdrawn from zone 11 by line 18 and is discharged thereby into a stripping zone 19 which is provided with a heating means 20 which is illustrated by an internal coil which will be understood to embody any of the well known types of heating means available to the industry. Stripping zone 19 is provided with internal baffling equipment to allow separation of the phenol from the hydrocarbon constituents contained therein which will be the more aromatic and naphthenic constituents as opposed to the more paraffinic constituents which will be found in the solvent raffinate. The phenol is removed from stripping zone 19 by line 21 for reuse in the process while the predominantly aromatic and naphthenic constituents removed from the mineral motor oil distillate as a solvent extract are discharged from stripping zone 19 by line 36 to be used as a cracking stock or in other uses as may be desired.

A solvent raffinate is removed from extraction zone 11 by line 22 and is discharged thereby into a stripping zone 23 which is similar to stripping zone 19 and is provided with a heating means illustrated by coil 24 which may be any of the well known heating means available to the industry. Zone 23 is provided, like zone 19, with internal contacting equipment to allow separation between the phenol and the predominantly paraffinic constituents found in the solvent raffinate. Conditions are adjusted in stripper 23 to remove phenol by line 25 while

the desired motor oil components are removed from zone 23 by line 26.

When sodium hydroxide or sodium phenolate is not added to the phenol, alternatively it may be added to the solvent raffinate in line 22. When this is desired, valve 15 in line 14 is closed and valve 21 in line 28 is opened, allowing line 28 to be connected to line 14, pump 17, and tank 16, and allowing the sodium hydroxide to be introduced into the solvent raffinate containing phenol to cause formation in situ of sodium phenolate and allow the obtaining of a raffinate having an organic acid content corresponding to a neutralization value no greater than 0.1 milligram KOH per gram of oil. When the latter operation is employed, it will be understood that a suitable incorporation means, not shown, will be provided in line 22 to allow intimate admixture of the solvent raffinate with the sodium hydroxide or sodium phenolate introduced thereto by line 28.

When the sodium phenolates are formed by introduction of sodium phenolate or sodium hydroxide to line 22, it may be desirable to contact the phenol-free oil, which may contain small quantities of sodium phenolates, with clay. Therefore, a clay contacting zone 29 is provided wherein the oil containing small quantities of sodium phenolate may be contacted at a relatively high temperature such as in the range of 350° to 450° F. with a suitable contact clay such as illustrated by acid treated natural clays or bentonite, and the like. When this operation is conducted, valve 30 in line 26 will be opened, valve 31 in line 32 will be closed, and valve 33 in line 34 will be opened, allowing the oil to be routed by line 26 to clay contacter 29 where it is intimately admixed with clay, which is subsequently removed from the oil by means not shown; and the clay-treated oil discharged from zone 29 by line 34 into line 32, cooled in cooler 35 in line 32, and discharged thereby to suitable storage facilities, not shown, from whence the oil may be withdrawn for use as a commercial lubricating oil having a neutralization value no greater than one milligram KOH per gram of oil.

When the sodium hydroxide or sodium phenolate is introduced into the phenol by line 14 connecting into line 13, the employment of clay contacting zone 29 may be dispensed with and the oil may bypass this zone by closing valve 30 in line 26 and valve 33 in line 34. With valve 31 in line 32 in the open position, the motor oil substantially free of phenol is routed by line 26 and line 32 through cooler 35 to storage for use as a commercial motor oil having the desired low neutralization value as mentioned before.

Although the invention has been described and illustrated above with respect to tank 16 containing sodium hydroxide, it will be apparent that this tank may contain alkali metal hydroxide such as sodium hydroxide or an alkali metal phenolate. Thus, provision is made by line 7, controlled by valve 8, to introduce alkali metal hydroxide to tank 16 and provision is also made to introduce alkali metal phenolate thereto by line 9, controlled by valve 10.

While the invention has been described and illustrated with respect to employment of sodium phenolate or sodium hydroxide, it is to be understood that the phenolates or hydroxides of the other alkali metals, such as lithium and potassium phenolates or hydroxides, may be employed in lieu of sodium hydroxide or sodium

phenolate, but that the latter are to be preferred by virtue of their cheapness and availability.

In the present invention it will be obvious to those skilled in the art that the critical quantity of alkali metal hydroxide or alkali metal phenolate introduced into the solvent extraction system will depend on the concentration of organic acids contained in the lubricating oil fractions subjected to the process of the present invention. The organic acid content of the lubricating oil distillate must be reduced sufficiently to permit obtaining the highest possible yield of solvent extracted lubricating oil meeting viscosity index and acid content requirements. On the other hand, the quantity of alkali metal hydroxide or alkali metal phenolate introduced into the extraction system should be sufficient to react with the organic acid content of the motor oil fraction without providing such an excess amount that the phenol will be reacted with and cause loss of the valuable solvent. In general, it is preferred to employ an amount of alkali metal hydroxide or phenolate in either the solvent or raffinate phase that is about theoretically equivalent to the amount of KOH required to neutralize acids in either the oil charge or remaining in the raffinate phase; however, on a molar basis, as little as 0.2 mol alkaline material per mol of KOH (determined from the neutralization value) may be used where the treating conditions are such that the phenol solvent is sufficiently selective to remove most of the acids. On the other hand, as much as 3 mols alkaline material per mol of KOH required to neutralize the acids may be used under extreme conditions where substantially complete removal of the organic acids from the oil is desired and where the acids are difficult to extract.

The conditions employed in the solvent extraction zone II may vary with the composition of the feed stock charged. In the case of treating distillates derived from coastal crudes, oil to solvent ratios in the range from 1:0.5 to about 1:3.0, treating temperatures in the range from about 100° to 250° F., and essentially atmospheric pressures are generally satisfactory. As mentioned before, the phenol may be substantially anhydrous or may contain up to about 10% by volume of water.

In order to demonstrate the invention further, the following examples are given which should not be construed as limiting the invention in any manner.

Example I

A motor oil distillate having a Saybolt Universal viscosity of approximately 950 seconds at 100° F., a viscosity index of 24, and a neutralization value of 1.25 milligrams KOH per gram of oil was extracted with 100% phenol using an oil to solvent ratio of 1:1.5. The extraction was carried out in a tower having five theoretical stages with a top tower temperature of 150° F. and a bottom temperature of 100° F. A 43% yield, based on the charge, of raffinate having a viscosity index of 68 and a neutralization value of 0.085 milligram KOH per gram of oil was produced during the extraction operation. In this particular operation it was desired to produce a solvent raffinate meeting a viscosity index specification of 60 and a neutralization value specification of less than 0.1 milligram KOH per gram of oil, but it was necessary to overextract the oil to meet the neutralization value specification.

Example II

In this operation, the motor oil distillate of Example I was treated with anhydrous phenol in the ratio of one volume of oil per volume of solvent in the treating tower described in Example I. Prior to the extraction operation, 0.2% by weight of 50° Bé. sodium hydroxide solution was added to the phenol. This amount of sodium hydroxide corresponds to 0.1% by weight of the phenol, and, based on the ratio of oil to solvent used in the extraction step and the neutralization value of the oil charge, is equivalent on a molar basis to 1.1 times the theoretical amount of KOH required to neutralize organic acids in the oil treated. The tower temperature conditions were the same as those employed in Example I. The yield of solvent raffinate in this operation was 56% by volume of the motor oil charged and had a viscosity index of 61. The neutralization value of raffinate was 0.059 milligram KOH per gram of oil, which is well below the specification requirement in this particular case.

Example III

In this particular operation, the same ratio of oil to solvent and the same temperature conditions were used in the treating step that were used in Example II. A 56% yield of raffinate having a viscosity index of 61 was obtained. In this operation, however, sodium hydroxide was not added to the anhydrous phenol prior to the extraction step, and the neutralization value of the raffinate was 0.308 milligram KOH per gram of oil, which is greatly in excess of the specification figure and of the neutralization value of the raffinate produced in Example II.

It will be observed from the foregoing examples that the present invention allows vastly improved results both in yield and quality of finished product without resorting to overextraction thereof. It is further noted that the invention permits employing much lower solvent treats than are conventionally permitted to obtain a product having a low neutralization value by employing a small amount of sodium hydroxide or sodium phenolate in the solvent instead of a relatively large amount of solvent to remove acidic bodies from the oil.

It should be mentioned that anhydrous phenol was employed in the foregoing examples, and, therefore, the yields of finished raffinate were somewhat lower than would be obtained by using aqueous phenol. For example, a distillate similar to that used in the Examples but having a 1.5 neutralization value may be treated at a temperature of 165° F. with a mixture comprising 96% phenol and 4% water (oil to solvent ratio of 1:1.5) to obtain a 63% yield of raffinate having a viscosity index of 68 and a neutralization value of 0.08 milligram KOH per gram of oil. By adding a small amount of an alkali metal hydroxide as taught in Example II, or sodium phenolate if so desired, to the solvent, it is possible under the same temperature conditions using the 96% phenol and an oil to solvent ratio of 1:1.25 to obtain a higher yield of raffinate than obtained at the high solvent treat meeting viscosity index and neutralization value specifications. Since anhydrous phenol is somewhat more selective to acidic bodies in the oil than is the aqueous phenol, it is generally necessary to use a slightly higher amount of alkali metal hydroxide or phenolate based on the acidic bodies and/or a higher solvent treat when using the latter material as compared to the anhydrous phenol.

It is, therefore, seen that by practicing the present invention, it is possible to remove acidic bodies from lubricating oil distillates by a modified solvent which comprises phenol and a small amount of an alkali metal hydroxide or phenolate which has a greatly improved selectivity for the acidic constituents. It is possible to obtain an extracted oil meeting both neutralization value and viscosity index requirements without resorting to overextraction which causes the loss of valuable lubricating oil constituents. Such high viscosity index constituents where overextraction occurs are lost in the solvent extract and, therefore, are degraded to cracking stocks whereas in the practice of the present invention, these valuable constituents may be used as lubricating oil components.

The nature and objects of the present invention having been completely described and illustrated, what we wish to claim as new and useful and to secure by Letters Patent is:

1. A method for solvent extracting a mineral lubricating oil distillate fraction which contains small quantities of naturally occurring naphthenic acids, has a neutralization value in the range from about 1 to about 3.5 milligrams KOH per gram of oil and would be over extracted if extracted with phenol alone in such an amount as to reduce its acid neutralization value below .1 milligram KOH per gram of oil, which comprises the steps of intimately contacting said fraction with a phenol solvent containing no more than 10% water and a small but effective amount of an alkali metal phenolate equivalent to from 0.2 to 3.0 times the theoretical amount of KOH required to neutralize acidic bodies in said fraction under conditions including a temperature in the range between 100° and 250° F. and substantially atmospheric pressure to form a raffinate phase and an extract phase and separately recovering said phases.

2. A method in accordance with claim 1 in which the phenolate is formed in situ by adding to said phenol solvent an alkali metal hydroxide in an amount in the range from 0.2 to 3.0 times the theoretical amount of KOH required to neutralize acidic bodies in said fraction.

3. A method in accordance with claim 1 in which the alkali metal is sodium.

4. A method in accordance with claim 1 in which the alkali metal is potassium.

5. A method in accordance with claim 1 in which the alkali metal is lithium.

6. A method for solvent extracting a mineral lubricating oil distillate fraction which contains small quantities of naturally occurring naphthenic acids, has a neutralization value in the range from about 1 to about 3.5 milligrams KOH per gram of oil and would be over extracted if extracted with phenol alone in such an amount as to reduce its acid neutralization value below .1 milligram KOH per gram of oil, which comprises the steps of forming a first stream of said lubricating oil fraction, forming a second stream of phenol containing no more than 10% water, adding to said second stream an amount of an alkali metal hydroxide equivalent to from 0.2 to 3.0 times the theoretical amount of KOH required

to neutralize acidic bodies in said oil, contacting said first stream with said second stream under conditions including a temperature in the range from about 100° to 250° F. and substantially atmospheric pressure to form a raffinate phase and an extract phase, separating said phases, separately removing phenol from said separated phases, and recovering from said raffinate phase a motor oil fraction having a neutralization value less than 0.1 milligram of KOH per gram of oil.

7. A method for solvent extracting a mineral lubricating oil distillate fraction which contains small quantities of naturally occurring naphthenic acids, has a neutralization value in the range from about 1 to about 3.5 milligrams KOH per gram of oil and would be over extracted if extracted with phenol alone in such an amount as to reduce its acid neutralization value below .1 milligram KOH per gram of oil, which comprises the steps of contacting said distillate with phenol solvent containing no more than 10% water under conditions including a temperature in the range between 100° and 200° F. and substantially atmospheric pressure to form a raffinate phase and an extract phase, separating said phases, maintaining in said raffinate phase a small but effective amount of an alkali metal phenolate equivalent to from 0.2 to 3.0 times the theoretical amount of KOH required to neutralize acidic bodies in said fraction, separating phenol from said raffinate phase, and recovering from said raffinate phase a lubricating oil fraction substantially free of said acidic bodies.

8. A method in accordance with claim 7 in which said lubricating oil fraction substantially free of said acidic bodies is treated to remove sodium phenolate therefrom.

9. A method in accordance with claim 7 in which said phenolate is formed in situ by adding to said solvent raffinate an alkali metal hydroxide in an amount equivalent to from 0.2 to 3.0 times the theoretical amount of KOH required to neutralize acidic bodies in said raffinate phase to obtain a motor oil having a neutralization value less than 0.1 milligram KOH per gram of oil.

10. A method in accordance with claim 7 in which the alkali metal is sodium.

11. A method in accordance with claim 7 in which the alkali metal is potassium.

12. A method in accordance with claim 7 in which the alkali metal is lithium.
